UNITED STATES PATENT OFFICE.

EDWARD H. KELLY, OF HARTFORD, CONNECTICUT, ASSIGNOR TO COLT'S PATENT FIRE ARMS MANUFACTURING COMPANY, OF HARTFORD, CONNECTICUT, A CORPORATION OF CONNECTICUT.

DESIGN FOR A REVOLVER.

Application filed March 29, 1926. Serial No. 17,092. Term of patent 14 years.

To all whom it may concern:

Be it known that I, EDWARD H. KELLY, a citizen of the United States, residing at Hartford, in the county of Hartford and State of Connecticut, have invented a new, original, and ornamental Design for Revolvers, of which the following is a specification, reference being had to the accompanying drawing.

Of the drawing,

Fig. 1 is a plan view of a revolver embodying my new design.

Fig. 2 is a side view of the revolver.

In the drawing the portions of the revolver constituting my novel design are shown

in full lines, and other portions of the revolver are shown in dotted lines. The stippled portions of the drawing, representing parts of the front sight and of the top of the frame adjacent the rear sight, are intended to indicate a dull or non-reflecting finish, whereas the other shaded portions of the drawing are intended to indicate highly polished surfaces. The short parallel vertical lines in Fig. 1 represent transverse serrations.

I claim:

The ornamental design for a revolver as shown and described.

EDWARD H. KELLY.
